UNITED STATES PATENT OFFICE

2,488,308

TROLLEY SECTION INSULATOR

Samuel S. Matthes, Mansfield, Ohio, assignor to
The Ohio Brass Company, Mansfield, Ohio, a
corporation of New Jersey

Application August 21, 1946, Serial No. 692,036

7 Claims. (Cl. 191—39)

1

My invention relates to insulators for sectionalizing the trolley wire of overhead trolley systems and has particular reference to providing means killing the arc which forms when a car crosses the insulator with current on the motors.

One object of my invention is to provide magnetic means for dissipating and extinguishing the arc which forms to avoid as much injury to the adjacent parts of the device as possible.

Another object is to divide or split the arc which is forced upward by the magnetic means, thereby aiding in reducing the effects of the arc upon the adjacent parts.

Other objects will appear as the description of my invention proceeds.

Fig. 1 is a side view in elevation in partial section of my invention.

Fig. 2 is a section on the line 2—2 of Fig. 1.

Fig. 3 is an end view in elevation of one form of the magnetic blow-out means employed.

Fig. 4 is an end view in elevation of another form of the magnetic blow-out means employed.

The sectionalizing device proper comprises a pair of metal end members 1 with trolley tips 2 secured thereto by bolts 3 and each tip is provided with means 4 to receive and hold the end of a trolley wire 5.

The end members are held in spaced and insulated relation by means of the tension member 6 and the compression member 7.

Each end member is provided with a threaded socket to receive the threaded end of the member 6 and the member 7 is held in place by the screw 8 at each end thereof.

Below the member 6 extends a bridging member 9 of insulating material to guide a current collector across the device and having its ends mounted in end openings 10 in the metal yoke shaped support members 11.

The lower portion of the member 11 is aligned with the lower surface of the trolley wire 5 and with the lower portion or guiding surface of the bridging member 9 whereby the device offers smooth and unobstructed passage across the device.

Spaced from one end member 1 and support member 11 is a metal contact 12 also aligned with the members 9 and 11 coextensive with the member 9 thus avoiding an arcing gap at their abutting ends. Adjacent the inner end of the contact member 12 is provided magnetic blow-out means 13 to act upon any arc formed at the inner end of the member 12.

The blow-out means comprises a yoke 14 formed preferably of a single piece of magnetic 55

2

metal such as soft wrought iron and having legs or pole pieces 15 connected by member 16 which acts as the core for the energizing coil 17.

The legs 15 project downward opposite the inner end of contact 12 and spaced therefrom sufficiently to allow the free passage of a current collector shoe or wheel.

The yoke 14 is supported from the compression member 7 by the two-part clamp members 18 held to the member 7 by bolt 19 and to the yoke member 14 by screws or bolts 20.

To prevent the arc formed at the inner end of the member 12 attacking the metal legs 15 and member 16, insulation 21 is provided held to the legs 15 by the screws or bolts 22. The insulation lining may be formed of one or several pieces.

Interposed between the arms 15 and tension member 6 are members 23 (Fig. 2) of insulating material by means of which any arc formed on either side of the longitudinally extending member 9 will be further split or divided two-ways. These members are held in place by fasteners 24.

These members 23 are triangular in shape (Fig. 1) with the apex below and shown in vertical alignment with the end of the contact member 12.

The coil 17 has its terminals 25 and 26 electrically connected to the contact member 12 and adjacent end member 1 respectively, thereby being energized when a current collector engages the contact member 12 and drawing motor current. The energization of the coil and direction of flow of the magnetic flux between the legs 15 depends upon the connections to the contact and end members and is preferably connected to cause the arc to be driven upward.

By having the apex of the members 23 below, the division of the arc formed laterally on each side of the member 9 is assured.

The insulating parts which are subject to the effect of the arc are made of combustion resisting material of which there are several to be secured on the market.

Section insulators have been proposed with magnetic blow-outs, some with chutes with partitions therein for splitting or dividing the arc and some with no means whatsoever to divide the arc formed on the sides of the bridging member, but my invention is the first it is believed to attempt a section insulator without the use of an arc chute but with the means described to split the arc.

The members 23 aid in bracing the legs of the blow-out device 14 with respect to the member 6.

When an arc is formed at the inner end of the

contact member 12, it divides with respect to the bridging member 9 and is then driven upward by the magnetic flux between the legs 15 and when the arcs strike the dividers 23 the arcs are each again split at right angles to the first division making a total of six divisions for the original arc thus greatly reducing their burning effect upon the parts above.

The members 23 may be secured to the insulating member 6 in place of to the blow-out legs or poles. The combined functions of the guide 9 and members 23 operate to divide the arc formed at the leaving end of the contact member 12, four-ways.

In Fig. 4, a portion of the legs 15 is formed with an off-set to permit winding the energizing coils 17 on the off-set portion of each leg and securing the arc-dividing members 23 to the insulating members 21. The construction shown in Fig. 4 has been found to have advantage over that of Fig. 3 in that the coils extend along the legs 15 and down to a point where the transverse flux or flow of the magnetic lines drives of force takes place which is opposite the point where the arc is formed thus increasing the blow-out effect.

Having described my invention, I aim in my claims to cover such arrangements and modifications which do not involve a departure from the spirit and scope of my invention.

What I claim as new is:

1. In a section insulator for an overhead trolley wire comprising a pair of spaced end members of metal held in spaced relation by insulating means and a current collector guide member of insulating material extending between the end members and a contact member of metal associated with the guide in spaced relation to the end members and having its inner end abutting that of the guide member, the combination with the insulating means of electro-magnetic blow-out means to extinguish an arc formed at the leaving end of the contact member; the blow-out means comprising a pole positioned on each side of the abutting ends of the guide and contact member and spaced therefrom and an energizing coil wound upon a core connecting the poles and having its terminals connected to an end member and to the contact member whereby the said arc will be directed upward away from the guide when a current collector breaks engagement with the contact member and means on each side of the device and positioned above the lower edge of the guide to divide the arc formed on each side of the guide longitudinally of the guide member.

2. A device to sectionalize an overhead trolley wire comprising a pair of metal end members to receive the ends of the trolley wire and held in spaced relation by elongated insulating means, a current collector guide of insulating material extending between and supported by the end members and a metal contact associated with the guide and spaced from one end member and having its side and guide surfaces coextensive and in surface alignment with those of the said guide, the contact member engageable by the current collector and a magnetic blow-out supported by the insulating means with a pole piece on opposite sides of the guide adjacent the leaving end of the contact member, a coil connected to the contact member and an adjacent end member and arranged to energize the pole pieces when a current collector engages the contact member and to extinguish an arc formed at the leaving end of the contact member, the insulating guide

means arranged to divide the arc laterally and means positioned between the pole pieces of the blow-out means longitudinally of the guide to divide the arc formed on opposite sides of the guide.

3. In a device to sectionalize an overhead trolley wire and guide a current collector across the device comprising an elongated insulating means with a metal end member at each end of the means and a metallic contact member intermediate the end members in insulated relation to the end members and engageable by the current collector in crossing the device, the combination with the insulating means of electro-magnetic means to control any arc formed at the leaving end of the contact member, the said magnetic means comprising an insulating member to guide a passing current collector and extending from the leaving end of the contact member to the leaving end member of the device to divide laterally any arc formed at the leaving end of the contact member when the current collector passes onto the insulating member, magnetic poles disposed on opposite sides of said device where the arc is formed and coil means arranged to energize the poles when the current collector engages the contact member, the coil means connected to the contact member and the entering end member whereby the coil means may be energized, and means associated with the magnetic means to divide longitudinally the arc formed on each side of the insulating member two-ways whereby the arc formed at the end of the contact member will have been divided six-ways.

4. A section insulator for an overhead trolley comprising a pair of metal end members held in spaced relation by a pair of spaced and parallel elongated insulating means and a guide member of insulating material for a current collector, a contact member of limited length associated with and abutting an end of the guide member and engageable by the current collector, blow-out means comprising an electro-magnet frame of magnetizable metal having a U shape formation with depending poles spaced on opposite sides of the leaving end of the contact member to act upon and control an arc formed at said end and a coil wound on the bight of said frame connecting the poles at one end thereof to energize the poles, the coil connected to the contact member and one end member, means secured to the blow-out means and to one of the insulating means to support the blow-out means, the coil connected to drive the arc upward and exposed means on opposite sides of the insulating means in the path of the moving arc to divide the arc as it moves upward, the exposed means engaging the other of the insulating means to steady the blow-out means transversely of the guide means.

5. A magnetic type arc blow-out device comprising a yoke shaped member of magnetizable metal having a pair of spaced and substantially parallel poles connected at one end by a member of like metal, energizing coil means associated with a portion of the yoke shaped member to magnetically energize the poles, a triangular shaped member associated with each pole between the poles and in spaced relation to each other, the apex end of the triangular shaped members positioned adjacent to but not at the free ends of the poles whereby any arc formed intermediate the poles may be directed toward the said triangular shaped member and

divided thereby, longitudinally extending insulating means positioned between the said triangular shaped members and embraced by the said members to steady the yoke shaped member, separately formed means detachably secured to the yoke shaped member and positioned above the yoke shaped member, and longitudinally extending insulating means gripped by the separately formed means to support the yoke shaped member.

6. The sectionalizing device for a trolley wire of an overhead trolley system comprising a pair of metal end members to receive the ends of the trolley wire and the end members held in spaced relation by elongated insulating means, longitudinally extending current collector guiding means extending between the inner ends of the end members, the guiding means comprising an extended insulating portion and a metallic portion energized from the adjacent end member whereby an arc is formed as a passing current collector leaves the said metal portion and moves onto the extended insulating portion, the side and lower surface of the said portions being aligned, the insulating portion dividing the arc laterally two-ways, the adjacent ends of the said portions abutting, magnetic means supported by the said elongated insulating means having its poles positioned on opposite sides of the abutting ends of the insulating and metallic portions and spaced laterally therefrom to control the arc, means positioned between the poles of the magnetic means above the guiding means to split the arc on each side of the guiding means two-ways and parallel to the guiding means.

7. In a device arranged to sectionalize the trolley wire of an overhead system, and having a

- 5 live contact member abutting an insulating guide member at which point an arc is formed, the combination therewith of an arc blow-out means secured to the device and operating to divide and disperse the said arc when formed, the said means comprising an electro-magnetic frame so constructed and arranged relative to the said abutting point as to pass lines of force transversely of the said guide and contact member at their abutting point when a current collector engages the contact member to control the directional movement of the arc and to dissipate same, means associated with the blow-out means and under influence of the lines of force to divide the arc formed on each side of the guide member at the end of the contact member two-ways.
